UNITED STATES PATENT OFFICE.

HERMAN A. J. RIECKERT, OF NEW YORK, N. Y.

SPRING-HINGE.

SPECIFICATION forming part of Letters Patent No. 453,503, dated June 2, 1891.

Application filed August 20, 1890. Serial No. 362,513. (No model.)

To all whom it may concern:

Be it known that I, HERMAN A. J. RIECKERT, of the city, county, and State of New York, have invented a new and Improved Hinge, of 5 which the following is a full, clear, and exact description.

The invention relates to hinges such as shown and described in the application for Letters Patent of the United States, Serial 10 No. 341,270, filed by me February 21, 1890, and allowed May 1, 1890.

The object of the present invention is to provide a new and improved hinge, which is simpler and more durable in construction 15 than the one above referred to and is very effective in operation.

The invention consists in certain parts and details and combinations of the same, as will be described hereinafter, and then pointed 20 out in the claims.

Reference is to be had to the accompanying drawings, forming a part of this specification, in which similar letters of reference indicate corresponding parts in all the figures.

25 Figure 1 is a sectional side elevation of the improvement. Fig. 2 is a sectional plan view of the same on the line $x-x$ of Fig. 1. Fig. 3 is a transverse section of the same on the line $y-y$ of Fig. 1, and Fig. 4 is a sectional plan 30 view of the same on the line $z-z$ of Fig. 3.

The improved hinge is provided with a suitably-constructed tube or casing A, fitted into a suitable recess in the door and held in place by the U-shaped side plate A' and the 35 bottom plate A², screwed or otherwise fastened to the door. The upper end of the tube or casing A is closed by a nut B, against the under side of which presses one end of a spring C, held in the said tube or casing A 40 and pressing on top of a cam D, provided on opposite sides with lugs E, fitting into suitable guideways F, formed in the casing A. The cam D is thus prevented from turning in the casing A, but is free to slide vertically 45 therein.

On the under side of the cam D at opposite sides are formed the cam-faces D', adapted to engage friction-rollers G, journaled in the upper end of a pivot or pintle H, extending into 50 the casing A for the latter to turn thereon.

The pintle or pivot H is provided with a base

H', fitted into a casing I, secured to the door-sill and carrying a plate J for locking the base H', and consequently the pintle or pivot H, in place. The pintle or pivot H is provided 55 within the casing A with an annular recess H², into which fit friction-rollers K, mounted to turn loosely on studs L, projecting from nuts N, screwing in the casing A, as is plainly shown in the drawings, so that the weight of 60 the door is transmitted by the friction-rollers L to the pivot H, thus relieving the spring C, the cam D, and the friction-rollers G from the weight of the door. When the door is closed, the hinge is in the normal position shown in 65 Fig. 1—that is, the friction-rollers G are engaged by the upper parts of the cam-faces D'. When the door is opened, it swings on the pintle or pivot H as a fulcrum, and the cam D, moving with the door, travels, with its cam-face D', on the friction-rollers G, so that the 70 said cam D is caused to slide upward, being guided by the lugs E and the bearings F, and compressing the spring C. The moment the door is released the spring C, pressing on the 75 cam D, forces the latter downward, so that the door is returned to its former normal closed position. When the door is given nearly a full quarter swing, the lower horizontal part of the cam D stands on top of the friction- 80 rollers G, whereby the door is held in an open position, and is closed only when sufficiently moved to bring the lower end of the cam-faces D' onto the friction-rollers G. The spring C 85 will then force the door shut, as previously described.

The cam-faces D', as shown in the drawings, are made double, so that the door can swing in either direction, the action of the spring and cam being the same in both cases. 90 It is understood that by this construction of the hinge friction is reduced to a minimum.

Having thus described my invention, what I claim as new, and desire to secure by Letters Patent, is—

1. In a hinge, the combination, with a tube or casing and friction-rollers held therein, of a pivot or pintle entering the said casing and provided with an annular groove engaged by the said friction-rollers, substantially as 100 shown and described.

2. In a hinge, the combination, with a cas-

ing, of a spring held in the said casing, a cam fitted to slide vertically in the said casing and pressed on by the said spring, a fixed pintle or pivot entering the said casing and provided with an annular groove, friction-rollers held on the said pintle or pivot and adapted to be engaged by the cam-faces of the said cam, and a second set of friction-

rollers held on the said casing and engaging the annular groove of the said pintle or pivot, substantially as shown and described.

HERMAN A. J. RIECKERT.
